CLAIM

The ornamental design for a mobile drain pan for liquid storage and recovery, as shown.

DESCRIPTION

FIG. 1 is a side perspective view of the mobile drain pan for liquid storage and recovery showing our new design with the opposite side being a mirror image thereof;

FIG. 2 is a top plan view thereof;

FIG. 3 is a bottom plan view thereof;

FIG. 4 is a rear elevational view thereof; and,

FIG. 5 is a front elevational view thereof.
